UNITED STATES PATENT OFFICE.

JABEZ HEDGES AND WILLIAM HAMMACK, OF LANCASTER, OHIO.

AUXILIARY AIR-INTAKE VALVE.

1,142,424.

Specification of Letters Patent. Patented June 8, 1915.

Application filed September 8, 1914. Serial No. 860,745.

To all whom it may concern:

Be it known that we, JABEZ HEDGES and WILLIAM HAMMACK, citizens of the United States, residing at Lancaster, in the county 5 of Fairfield and State of Ohio, have invented certain new and useful Improvements in Auxiliary Air-Intake Valves; and we do declare the following to be a full, clear, and exact description of the invention, such 10 as will enable others skilled in the art to which it appertains to make and use the same.

Our invention relates broadly to improvements in valves and more particularly to those adapted for use for admitting air into 15 the intake manifold of an internal combustion engine.

The invention aims to provide extremely simple structure which may be readily attached to the intake manifold of an internal 20 combustion engine and structure which, although simple, will be highly efficient in operation.

The above mentioned construction employed for carrying out the objects of the 25 invention is described and claimed herein and shown in the accompanying drawings wherein—

Figure 1 is a side elevation of a carbureter and a portion of an internal combustion engine, showing the application of our invention to the intake manifold leading from the former to the latter; Fig. 2 is a vertical transverse section taken on the line 2—2 of 30 Fig. 1; and, Figs. 3 and 4 are horizontal sections taken upon the line 3—4 of Fig. 1 and showing respectively the position of the parts when warm air is to be injected into the mixture and the relation which these parts assume when warm air is to be prevented 35 from entering the mixture.

In the accompanying drawings, a portion of an internal combustion engine is illustrated which includes the usual intake manifold I and an exhaust manifold E. These 40 parts may be of any suitable construction and form no part of the present invention, the intake manifold being here shown as having a forked upper end which connects with the cylinders of the engine in a well 45 known manner, the upright portion of said inlet manifold being provided with an annular flange F on its lower end which is connected to the upper end of the Venturi tube of a carbureter C, the usual throttle 50 valve T being employed in said tube. The throttle valve T is here shown as provided

with an operating stem S to which a lever L is rigidly secured at its lower end, the upper end of said lever being pivotally connected to an operating rod R which may be shifted 60 by any suitable means indicated at M in the drawings, said means being preferably operated from the floor of an automobile when the device is employed in this connection.

Having its inner end threaded into the 65 upright portion of the intake manifold I, is a laterally projecting tube 1 which is formed with a passage 2 throughout its length and with a pair of globular enlargements 3 and 3' to which transversely extending 70 bosses 4 and 4' are integrally connected, said bosses being formed with bores 5 and 5' which intercept the bore 2, said bores 5 and 5' opening through the outer ends of the bosses as clearly seen in Figs. 75 3 and 4.

Slidably mounted within the bores 5 and 5' is a pair of slide valves 6 and 6' which are provided with transverse openings 7 and 7' adapted to register with the bore 2. The 80 valves 6 and 6' are provided with heads 8 and 8' on one end while their opposite ends project from the adjacent bosses and receive stop washers 9 which are preferably held in position thereon by means of cotter pins 85 10, coiled springs 11 being interposed between said washers and the adjacent ends of the bosses 4 and 4', whereby the openings 7 and 7' are normally moved out of alignment with the bore 2 and whereby the heads 90 8 and 8' are normally forced in contact with the ends of the bosses adjacent thereto.

Leading from the outer end of the tube 1 to a heating drum 12 which is secured on the exhaust manifold E by any suitable 95 means, is a warm air conducting tube 13 which is adapted to conduct heated air from said drum into the intake manifold I when the valves 6 and 6' are opened by means to be described.

Pivotally mounted in the bifurcated end 14 of an arm 15 secured to the flange F, is an upright lever 16 whose lower end is bifurcated as at 17 to straddle the rod R between the pair of stops 18 thereon, the 105 upper end of said lever being pivotally connected by means of a link 19 with the head 8' of the valve 6' whereby, when the rod R is shifted to open the throttle valve T, the valve 6' will be shifted to cause its opening 110 7' to register with the bore 2 within the tube 1. If the valve 6 is now open, warm air

may be drawn into the intake manifold to mingle with the mixture passing therethrough, but if the valve 6 is closed, it will be seen that although an additional amount 5 of mixture is fed to the engine cylinders, no warm air is allowed to enter the mixture. It will, therefore, be seen that it is expedient to provide means whereby the valve 6 may be positively held in open or closed position. 10 For this purpose we have provided a wire 20 which is connected at one end to the head 8 while its opposite end is connected to a lever 21, locked normally against movement by a rack 22, said lever and rack being preferably mounted adjacent the steering wheel W of the machine to which the previously described construction is applied, the intermediate portion of said wire passing through the tube or casing 23 as is common 15 with devices of this character. By this construction it will be seen that the valve 6 may be positively held in open or closed position thus allowing warm air to flow into the intake manifold when the valve 6' is 20 opened or preventing the entrance of air into said manifold, as the case may be. By so constructing and mounting the valves 6 and 6' the throttle valve T may be operated to vary the amount of mixture fed to the 25 engine cylinders without injecting warm air into said mixture, since the injection of the latter is not necessary in warm weather. When, however, it becomes necessary to raise the temperature of the mixture before feeding the same to the engine cylinders, this 30 being necessary in extremely cold weather, the valve 6 may be held in open position by the means previously described thus allowing a predetermined amount of warm air to 35 enter the intake manifold when the throttle valve T is opened, the amount of air allowed to enter being accurately regulated in order that the proportion of air and gas may remain normal. 40 45 We have described the valve 6 as being op-

erated by the lever 21 and the valve 6' as movable simultaneously with the rod R but it will be readily understood that the valve 6' could be operated by the lever 21 and the valve 6 by the rod R, since the effect would 50 be the same.

Having thus described our invention what we claim is:

1. A valve comprising a tube, a number of bosses formed on said tube and having bores intersecting the bore thereof, cylindrical valves slidable through the bores of said bosses and across the bore of said tube, said valves having openings adapted to register with said bore of the tube, and each of 55 said valves having one of its ends projecting beyond the adjacent bosses, stops on said projecting ends, coil springs located between said stops and said adjacent bosses, and independent means whereby said valves may be 60 operated.

2. A valve comprising a tube having its opposite ends threaded, two pairs of bosses formed on opposite sides of said tube and having bores registering with and intersecting the bore thereof, cylindrical slide valves in the bores of said bosses and having openings adapted to be moved into register with the bore of the tube, heads on one end of 70 said slide valves, the opposite ends thereof 75 projecting beyond the adjacent bosses, stops on said projecting ends, and coil springs encircling the latter between the stops and the adjacent bosses, combined with independent means whereby the two slide valves may be 80 operated.

In testimony whereof we have hereunto set our hands in presence of two subscribing witnesses.

JABEZ HEDGES.
WILLIAM HAMMACK.
